UNITED STATES PATENT OFFICE.

JOHN WIECHMANN, OF ALBANY, NEW YORK.

BOILER-FLUE CLEANER.

932,209.

Specification of Letters Patent. Patented Aug. 24, 1909.

Application filed November 27, 1907. Serial No. 404,062.

To all whom it may concern:

Be it known that I, JOHN WIECHMANN, a citizen of the United States, and a resident of Albany, in the county of Albany and

5 State of New York, have invented a new and Improved Boiler-Flue Cleaner, of which the following is a full, clear, and exact description.

The object of the invention is to provide a 10 new and improved boiler flue cleaner, arranged to insure a thorough removal of scale, and to provide the desired flexibility for the cleaner to readily pass through bent or curved tubes, flues or pipes.

15 The invention consists of novel features and parts and combinations of the same, which will be more fully described herein-after and then pointed out in the claims.

A practical embodiment of the invention 20 is represented in the accompanying drawings forming a part of this specification, in which similar characters of reference indicate corresponding parts in all the views.

Figure 1 is a side elevation of the improvement, parts being broken out; Fig. 2 is a 25 longitudinal central section of the same; Fig. 3 is an enlarged rear end view of the revoluble cutter head; Fig. 4 is a longitudinal section of the same on the line 4—4 of Fig. 3, and Fig. 5 is a transverse section of the initial cutter on the line 5—5 of Fig. 2.

The cutter-head A of the boiler flue cleaner is rotated by a turbine B of any approved construction, preferably, however, such as 35 shown and described in the application for Letters Patent of the United States, No. 370,866, filed by me on April 29, 1907.

The cutter-head A is mounted on a frame or spider C, having a front plate C', a rear plate C², and bars C³ connecting the plates C', C² rigidly with each other. The front plate C' is provided with a forwardly-extending centrally-arranged screw rod C⁴, on which screws the hub D' of an initial cutter D, having a plurality of radially disposed cutting blades D² curved forwardly and inwardly, to bring the forward ends of the cutting blades to a common point, as will be readily understood by reference to the drawings. The rear plate C² is provided with rearwardly-extending lugs C⁵ engaged by a pivot pin E also passing through the member E' of a universal joint having a pivot pin E² extending through the said member E' and 55 through lugs F' formed on the forward end of a motor or turbine wheel F, mounted to

turn in the forward end of a casing G, connected at its rear end by a ball and socket joint H with a coupling I, to which is attached a hose J connected with a fluid pressure supply, such as water under pressure, to cause the fluid under pressure to rotate the turbine wheel F and consequently the cutter head A.

In the forward plate C' of the frame or spider C are loosely fulcrumed the forward headed ends K³ of a plurality of spindles K, K' and K², arranged longitudinally and extending with their rear ends in elongated slots C⁶ formed in the rear plate C² of the frame or spider C, as plainly indicated in Figs. 3 and 4. On the spindles K, K' and K² are mounted to rotate loosely conical-shaped cutters L, L', L², extending between the plates C' and C² with their apex ends forward, and having lengthwise-disposed cutting edges L³, notched transversely in such a manner that the notches L⁴ follow a spiral line, as plainly indicated in Figs. 1 and 2. By the arrangement described each cutting edge L³ of a cutter L, L' or L² is divided by the notches into teeth, the teeth of successive cutting edges L³ breaking joint, owing to the notches being arranged in spiral form. The pitch of the cutting edges L³ for the several cutters L, L', L² is different, as plainly indicated in Fig. 3, to provide different teeth along the cutting edges of the several cutters, with a view to insure thorough cleaning of the flue when the device is in use, it being understood that successive teeth on each cutter and successive teeth on adjacent cutters act on different parts of the tube, to insure thorough cleaning thereof. The free or rear ends of the spindles K, K', K² are pressed outward by the action of a spring N, the outward movement being limited by the end wall of each of the slots C⁶ in the plate C² to prevent the cutters from cutting into the tube. The spindles are normally held in an outermost position by the segmental spring N, fitting into notches K⁴ formed on the rear terminals of the spindles K, K', K². By the arrangement described the spindles K, K', K² and their cutters L, L', L² are free to yield inwardly against the tension of the spring N, thus protecting the cutters L, L', L² against undue and quick abrasion when striking extremely hard matter which has to be cut out gradually. It will also be noticed that by the use of the spring, the cutters yield and hence are not liable to stick in

the tube. By the arrangement described the cutter head A when revolved by the turbine B and passing through a tube or flue to be cleaned, readily removes the scale therefrom, as the cutting edges of the blades D² cut into the material located near the center of the tube or flue, and then the cutting edges L³ of the cutters L, L', and L² come gradually in contact with the matter nearer to and at the inner surface of the tube or flue to be cleaned, so as to gradually and thoroughly cut the extraneous matter out of the tube. It is understood that the water passing through the turbine B readily washes the material cut loose in a forward direction, so as to enable the cutters D, L, L', and L² to properly cut at all times, unobstructed by the previously removed scale or other extraneous matter.

20. It will be observed from an inspection of Fig. 2, that the casing G is provided with a groove G', wherein is received a projection or pin G², from the ball Q' of the coupling. This connection permits a considerable flexibility of the casing with respect to the connection, but constrains the casing and connection to rotate together.

Having thus described my invention, I claim as new and desire to secure by Letters Patent:

1. A boiler flue cleaner having a rotatable cutter head consisting of a frame and a plurality of longitudinally extending rotatable cutters of conical form and provided with lengthwise arranged cutting edges notched transversely along a spiral line, the apex ends of the said cutters being forward and pivoted to the frame, and springs supporting the rear end and permitting them to yield inwardly.

2. A boiler flue cleaner having a rotatable cutter head consisting of a frame and a plurality of longitudinally extending rotatable cutters of conical form and provided with lengthwise arranged cutting edges of different pitch notched transversely in a spiral line, the apex ends of the said cutters being forward and pivoted to the frame, and

springs supporting the rear ends and permitting them to yield inwardly.

3. A boiler flue cleaner having a rotatable cutter head consisting of a frame, a plurality of longitudinally arranged spindles having their forward ends pivoted to the frame, conical cutters mounted to turn loosely on the said spindles and having the apex ends forward, the said cutters being notched transversely on a spiral line and springs supporting the rear ends of the spindles and permitting them to move inwardly.

4. A boiler flue cleaner having a revolvable cutter head comprising a frame, an initial cutter fixed on the forward end of the said frame and having radial cutting blades curved forwardly and inwardly to a common front meeting point, longitudinal spindles fulcrumed at their forward ends on the said frame and having their rear ends extending in radial slots in the said frame, conical cutters mounted to rotate loosely on the said spindles, and a spring removably connected with the rear ends of the said spindles.

5. A boiler flue cleaner provided with a revolvable cutter having longitudinally-extending cutting edges notched transversely along a spiral line.

6. A boiler flue cleaner provided with a revolvable head having a plurality of longitudinally-extending conical cutters having longitudinal cutting edges of different pitch, the cutting edges of each cutter being notched transversely along a spiral line.

7. A boiler flue cleaner provided with a revolvable cutter mounted for swinging movement at its forward end and spring-supported at its rear end, said cutter having longitudinally extending cutting edges notched transversely along a spiral line.

In testimony whereof I have signed my name to this specification in the presence of two subscribing witnesses.

JOHN WIECHMANN.
